Primary Examiner — Mary Ann Calabrese*Assistant Examiner* — Hillary Catherine Shepard(74) *Attorney, Agent, or Firm* — Alan D. Kamrath; Karin L. Williams; Mayer & Williams PC(57) **CLAIM**

The ornamental design for an extension table, as shown and described.

DESCRIPTION

FIG. 1 is a perspective view of an extension table showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines shown in the drawings depict portions of the extension table that form no part of the claimed design.
